UNITED STATES PATENT OFFICE.

JOSEPH WARREN CUTLER, OF ROCHESTER, NEW YORK.

MAIL-CHUTE.

SPECIFICATION forming part of Letters Patent No. 758,128, dated April 26, 1904.

Application filed September 14, 1903. Serial No. 173,070. (No model.)

To all whom it may concern:

Be it known that I, JOSEPH WARREN CUTLER, of Rochester, in the county of Monroe and State of New York, have invented certain new and useful Improvements in Mail-Chutes; and I do hereby declare the following to be a full, clear, and exact description of the same, reference being had to the accompanying drawings, forming a part of this specification, and to the reference-numerals marked thereon.

My present invention relates to mail-chutes adapted to extend vertically throughout a building, connected at its lower end to a mail-receiving receptacle and having apertures at various floors for the reception of mail-matter; and it has for its object to improve such devices, whereby access to the interior of the chute is facilitated for the purpose of cleaning the same or removing obstructions, and at the same time to provide a relatively smooth interior of such a nature that there are formed no cracks or crevices at the salient points of the chute into which the edges or corners of the descending mail-matter are liable to be caught and obstruct the chute.

The invention further has for its objects means for insuring the proper securing and fastening of the removable panels or sections and preventing their movement by unauthorized persons and, further, in an improved manner of supporting the chute-sections, whereby the erection of the same and the making of repairs, if necessary, are facilitated.

Heretofore mail-chutes have been usually constructed of a series of superposed sections embodying rear metal portions and fronts or covers of glass to facilitate inspection; but no means have been provided for affording access to the interior of the chute save through the mail-depositing aperture or by the removal of the entire section. The insertion of a wire through the mail-receiving aperture results oftentimes in destroying the covering of the mail-matter in the attempt to dislodge it. The removal of a chute-section requires the services of a skilled operator and the discontinuance of the use of the chute for a greater or lesser period, which would often times result in great inconvenience to the

users. These difficulties are, however, all obviated by the employment of a chute having a removable and preferably a hinged panel at one of the sides or walls and preferably at the front secured by suitable locking devices and having the joint between the edges of the removable panel and the walls of the chute removed from the corners or salient points or parts which are liable to be traversed by the edges or corners of the letters descending the chute, all as will be hereinafter described.

In the accompanying drawings, Figure 1 is a front elevation of that portion of the mail-chute extending between the ceiling and floor of one story of a building and showing one mail-receiving aperture. Fig. 2 is a vertical sectional view of the same. Fig. 3 is a side elevation of the upper portion of one of the chute-sections, showing the locking devices for the front or door. Fig. 4 is a horizontal sectional view on the line *y* *y* of Fig. 3. Fig. 5 is a vertical sectional view through the casing containing the door-securing device, showing the locking-bar and the door in side elevation and just before it is locked. Fig. 6 is a sectional view on the line *z* *z* of Fig. 5, showing the door or front panel closing. Fig. 7 is a sectional view on the line *A* *A* of Fig. 5. Fig. 8 is a horizontal sectional view on the line *B* *B* of Fig. 2. Fig. 9 is a horizontal sectional view on the line *C* *C* of Fig. 2. Fig. 10 is a perspective view showing the floor-section. Fig. 11 is a perspective view showing a chute extending through several stories of a building, and Fig. 12 is a perspective view of the wards of the lock and the key for co-operating therewith.

Similar reference-numerals in the several figures indicate similar parts.

As will be understood, the chute extends from the upper floors of a building to the lower floor, where it communicates with a suitable mail box or receptacle, which is under the control of the Post-Office Department, said chute forming a continuous passage for mail-matter, with apertures for the admission of mail-matter at each floor. In view of the well-known general appearance and operation of devices of this character I have deemed it necessary to show that portion of the chute

only which is arranged between the ceiling and the floor of one story of the building, as each of these is the same. In preparing the building for the mail-chutes it is only necessary to provide a suitable backing or support (indicated in the drawings by 1) and which may be of wood, metal, or other material extending vertically from the top to the bottom of the building and to provide in the floors adjacent this support suitable collars or tubes (indicated by 2) and preferably of sheet metal and slightly greater in size than the chute proper. At each of the floors of the building through which the chute extends and resting upon the latter is a hollow base-section 4, having at its rear side the cross-bar 5, which may be secured to the backing. The upper portion of this base-section embodies a vertically-extending flange 6, below which is a shoulder 7, and upon the latter is adapted to rest the lower edge of an adjustable section 8, preferably having a molding at its upper portion and for convenience termed a "molding-section," and near the rear edges of the sides inwardly-projecting flanges 9, Figs. 9 and 10, extending in rear of lugs or projections 10, formed on the downwardly-extending arms 11 of a bracket 12, secured to the support 1, the connection with the bracket permitting the vertical adjustment of the molding-section 8, but preventing its forward movement. The aperture in the upper end of the molding-section 8 is of a size adapted to fit upon the vertically-extending flange or apron 13, formed upon or secured to the upper end of the tube or floor-section 14, constructed of sheet metal slightly flared at its upper end, but with its main portion and lower end of substantially the internal diameter of the chute. This floor section or tube is supported at its upper end by the bracket 12, which latter is provided with undercut and preferably dovetail recesses 15, with which corresponding projections 15' of the floor-tube 14 coöperate. This construction is clearly shown in Figs. 2, 9, and 10. In the upper portion of Fig. 2 is shown the lower end of one of the tubes or floor-sections 14, which extend from the upper floor. As the several sections of the chute which are located between floors are constructed of uniform length, as will be described, and the lower end of the lowermost section is supported upon the bracket 12, it is desirable that the base portion of the chute adjacent the floor be capable of variation in height without showing any gaps or joints, and this is accomplished by the provision of the apron 13, with which the molding-section 8 coöperates. The portions of the chute extending between the ceiling and floor of each story of the building are divided into two or more sections of suitable length to be conveniently handled, two being shown in the present instance, and constructed in a similar

manner so far as general appearance is concerned. Each of these sections is preferably composed of a tubular body of sheet metal (indicated by 16) embodying a back portion, the side flanges 17 at the forward ends of which are provided the inwardly-turned flanges 18, the opening between said flanges 18 being closed by a removable panel, preferably in the form of a hinged door composed in the main by a sheet of transparent material, such as glass, through which the interior of the chute may at all times be inspected. Though I have in the present instance arranged the removable panel at the front and for obvious reasons prefer this, it may be generally referred to as located in one of the sides of the chute considered as a tubular structure. In the present instance this panel or door embodies a frame consisting of the vertical bars 19, connected at the upper and lower ends by cross-pieces 20, having their upper inner corners beveled or chamfered, as shown, the vertical bars 19 of the frame being covered by a heavy sheet-metal covering, the inwardly-projecting flanges 22 and 23 of which, being more or less elastic, engage and firmly hold the edges of the front glass panel 21, extending from end to end of the door or section. The forward flange 22 of the sheet-metal covering for the door-frame is formed into a molding, as shown, presenting an ornamental appearance and also carrying the glass at the rear portion of the frame.

It is particularly important that the joint formed by the meeting edges of the chute-walls and removable panel or door be of such nature that the descending mail-matter shall not catch therein, and for this reason not only are these joints removed from the corners of the chute, but the sides of the panel or door are extended inwardly or toward the center beyond the inner faces of the flanges 18, so that there are no projecting portions or cracks accessible from the center of the chute into which the corners or edges of descending mail-matter could project and lodge. In the present embodiment this is accomplished by forming the inner flanges 23 of the door-casing with an offset toward the rear, serving to produce the inwardly-extending shoulders extending in rear of flanges 18, throwing the rear face of the glass substantially in line with the flanges and to some extent bracing the sides of the chute and preventing its losing its shape.

The front door or panel is in the present instance hinged upon the pintle or pintles 24, preferably approximately in line with the rear of the front glass, so that the door will move more nearly toward and from the front opening, the members of the hinges being preferably separate plates, as shown, or formed on the body and door, respectively, though I prefer the separate hinge members shown, as they serve to stiffen the parts. The edges of the glass panel preferably engage suitable stops, 130

formed in the present instance by the bars 19, which prevent sidewise motion of the glass.

The general construction of the sections provided with the doors are similar in all respects, excepting that in one of them is located the casing containing a mail-receiving aperture, which may be of any desired or suitable construction, but preferably embodying a casing attached to the front door, having an aperture at its upper side and a deflecting plate pivoted therein near its lower end, said plate having an angular portion at its upper end and being pivoted to move said angular portion beneath the aperture to close it when desired, suitable locking devices being provided capable of manipulation by a removable key. The upper and lower ends of the chute-sections 16 are provided with U-shaped stiffening frames or yokes 26, having at the rear undercut or dovetail projections 27, adapted to enter suitable recesses in supporting-brackets secured to the backing or support 1. The projections 27 at the lower end of the lower chute-section are adapted to enter the recesses 15 in the bracket 12, those at the upper end of said section at the corresponding recess formed in the intermediate bracket 28, also secured to the support 1, and the projections at the lower end of the upper section also enter recesses in said bracket 28. This section rests upon the upper end of the lower chute-section. The projections at the upper end of the upper section (shown in the drawings) engage in corresponding recesses formed in the upper bracket 29. The section 81, which corresponds to the molding-section 8, is slightly different in form in order to constitute a molding or cornice, the upper end of which is adapted to coöperate with the ceiling of the story and make a finished joint therewith. Also supported upon the bracket 29 is a section 131, corresponding to the apron or flange 13 at the bottom, excepting that it does not form a part of the floor-section 14 of the chute; but the lower end of the upper floor-section 14 passes within it, as shown in Fig. 2. This section 131 is provided at its lower rear side with undercut or dovetail projections 161, which rest in the corresponding recesses in the bracket 29 and secure the parts in position. The lower portion of section 81 is adjustable upon the section 131, thereby permitting slight variations in the adjustment of these parts to give a finished appearance, and is secured by screws or bolts passing through the section 81 and through slots in the section 131. The abutting edges of the sections and doors are covered or closed by U-shaped strips or cover-pieces 30, extending around the abutting ends of the sections and doors and secured by screws 31, as shown in Fig. 8.

In order to firmly secure the doors or movable front panels of the chute-sections and to provide for opening the chute only by authorized persons, I provide securing devices be-

tween the free edges of the doors and chute by arranging upon the edge of the door or panels, studs or projections 33, at suitable intervals in the length thereof, and provide upon the sides of the chute-section a vertically-movable locking-bar 34, having slots through which project guide-pins 35 and on the outer edge of which I provide locking-plates 36, having the curved slots 37 therein opening at their forward side, with which the studs or projections 33 on the doors are adapted to coöperate. The relation of the slots of the locking-plates 36 to the studs 33 is such that when the locking-bar 34 is in the lower position (shown in Fig. 3) the doors are held firmly in position and cannot be opened excepting by the manipulation of said locking-bar; but when said bar is raised to the position shown in Fig. 5 not only is the door disengaged, but the lower inclined portion of the slots in the locking-plate will force the door open to the position shown in said figure, permitting the studs to pass out freely when the door is swung open. In order to maintain the locking-bar in this position and to prevent the stud from striking the hooked ends of the locking-plates, I maintain said bar in its upper position by means of a latch 96, pivoted to the side of the chute and within a suitable casing and having a shoulder or projection 97, adapted to engage a notch in said bar, a portion of said latch below the pivot being adapted for engagement by a projection 98, attached to the front of the door, so that while the door is maintained in open position the locking-bar will be held raised; but when it is positively moved inward in order to close it the projection on the door will raise and release the catch, thus allowing the locking-bar to fall, but not until the studs on the door have entered the cam-slots sufficiently to insure the proper securing operation. The locking-bar may be manipulated by any suitable handle; but I prefer to employ a key-lock in connection therewith, so that the chute cannot be opened except by authorized persons. In the present embodiment the operating-handle 39, pivoted in a supplemental lock-casing 40, is provided with a plate 41, having a crank-pin 42 thereon, operating in a slot 43 in the locking-bar, said plate 41 also having on its periphery a cut-away portion 44, with which at times is adapted to coöperate the periphery of a locking-disk 45, also having a cut-away portion 46, adapted to receive the periphery of the plate 41, connected to the handle. The locking-plate 45 is pivoted upon a centering-stud 47 and provided with a recess 48, adapted to receive the end of the removable key 49, having notches or key-ways in its periphery adapted to coöperate with projections or wards 50 50* in the slotted disks 51, located in a suitable casing 52, secured to the outer side of the supplemental lock-casing 40. The relative arrangement of

the coöperating locking-disks 41 and 46 is such that when the handle 39 is turned to the vertical position to move the locking-bar into locking position to secure the door the cut-away portion 44 is in line with the concentric portion of the locking-disk 45, and the lock being turned by its key to the position shown in dotted lines in Fig. 3 and the key removed it will be impossible to open the chute; but 5 when the proper key is inserted and the disk 45 is turned to the position shown in full lines in Fig. 5 the handle may be moved to release and force out the door, the locking-rod then being maintained in unlocked position by its 10 latch, as described. The supplemental lock-casing 40 consists in part of a plate formed, as shown in Fig. 6, in cross-section, having at the inner side the short flange 60, extending beneath the flange 61 of a securing-plate 15 62, riveted or otherwise secured to the outer side of the chute and provided with a flange 63, to which the rearwardly-extending flange 64 of the casing 40 is secured by means of screws 65. The screws 65 are when the device 20 is in position in proximity to the main support 1 of the chute, so that they cannot readily be removed to disengage the lock-casing without removing the chute-section; but when the chute-section is removed the lock-casing 40 can be disengaged by removing the 25 screws 65, bending it outward slightly until the flange 64 is forward of the flange of the plate 62 and then sliding the casing toward the front of the chute to disengage the flanges 60 30 and 61.

In Fig. 12 I have illustrated the ward-plates 51 of the form I prefer to employ, the outer one having the flange or ward 50 with the central slot 151 therein and the inner one 40 having the segmental ward 50* thereon with the slot 150, the key 49 being provided with the slots 49*, as shown, and the location of the wards and key-slots being such that the key 45 may be inserted in vertical position and turned, with the plate 45, to horizontal position, the shoulder at the end of ward 50 preventing further motion, and the ward 50* being then in the slot or keyway nearest the end of the key the latter cannot be withdrawn until 50 it is returned to vertical position again, and as the disk 45 coöperates with the disk 41, as described, the latter must also be returned to the position it occupies when the chute-cover is in locked position before the key can be 55 removed.

While I have shown a form of lock embodying the removable ward-plates 51 and the disks 41 and 45, I do not desire to be confined to this specific form, as others equally efficacious will occur to those skilled in the art.

In practice I prefer to arrange operating and locking devices for the two adjacent chute-sections at the upper portion of the lower section and at the lower portion of the upper 65 section in convenient position for manipula-

tion by the operator, though the parts are practically duplicates.

Mail-chutes constructed as herein described are readily constructed and manipulated, and by reason of the fact that access may be 70 had to the interior without dismantling the whole structure any obstructions improperly inserted may be removed and the interior of the glass cleaned when desired.

I claim as my invention—

1. A mail-chute embodying a plurality of superposed tubular sections, and having a laterally-movable panel at one side.

2. A mail-chute embodying a plurality of superposed tubular sections and having a 80 hinged panel for admitting access to the interior of the chute.

3. A mail-chute embodying a plurality of superposed tubular sections and having an independently-movable panel to permit access 85 to the interior of the chute without removing adjacent chute-sections.

4. A mail-chute having an opening at one side to permit access to the interior thereof and a removable panel for closing the opening, 90 the joint between the meeting edges of the panel and the chute opening toward the outer sides of the chute.

5. A mail-chute having an opening at one side to permit access to the interior thereof 95 and a removable panel for closing the opening having portions projecting inwardly beyond the meeting edges of the panel and walls of the chute.

6. A mail-chute having an opening at one side to permit access to the interior thereof and a removable panel for closing the opening, the meeting edges of the panel and walls of the chute being removed from the corners 100 of the chute and said panel having projecting portions extending inwardly beyond said meeting edges to prevent lodgment of mail-matter therein.

7. A mail-chute having an opening at one side to permit access to the interior thereof 110 and a removable panel for closing the opening, the sides of said panel projecting inwardly beyond the adjacent walls of the chute.

8. A mail-chute having an opening at one side narrower than the chute to permit access 115 to the interior thereof and a removable panel for closing the opening having its edges extending inwardly beyond the adjacent walls of the chute.

9. A mail-chute embodying a channel or body portion substantially rectangular in cross-section having an opening extending lengthwise thereof, and a door or panel hinged at one side of the channel and devices for securing it, the joints at the edges of the panel 120 being removed from the salient angles or corners of the section.

10. A mail-chute embodying the channel or body portion, open at the front and the metal frame hinged at the side of the opening em- 125

- bodying the inwardly-extending flanges and the glass panel secured between them and constituting a closure for said opening.
11. A mail-chute embodying the channel or body portion open at the front and having the flanges at the sides thereof and the metal door-frame hinged at the side of the opening embodying the inwardly-extending flanges, and the glass panel secured by the flanges in the frame, and held by them with its inner surface in substantially the plane of the flanges at the sides of the front opening in the channel.
12. A mail-chute embodying the channel or body portion open at one side and having the reinforcing strips at the ends in combination with a door or panel hinged at the side of the opening and arranged to cover the latter and securing devices for the free edge of the door.
13. A mail-chute embodying the channel or body open at one side in combination with a door or closure hinged near the edge of said opening embodying the connected sheet-metal side pieces having inwardly-extending flanges and a glass panel secured between said flanges.
14. A mail-chute embodying the channel or body open at one side having the flanges at the edges of said opening in combination with a door or closure embodying the side frames each provided with parallel flanges, and the glass panel secured between them, a portion of the door-frame extending between the flanges on the body.
15. A mail-chute embodying the channel or body open at one side, in combination with the hinged door or closure for the open side extending between the walls of the channel and serving to prevent the inward movement of the latter.
16. A mail-chute embodying a channel or body portion of sheet metal having the opening therein and the inwardly-extending flanges at the sides thereof, a frame hinged at one side of the opening having the glass panel therein and securing devices for the free edge of the frame.
17. A mail-chute embodying a plurality of superposed tubular sections open at one side and each provided with the panel hinged at the edge of the opening and locking devices for the free edge of said panel.
18. A mail-chute embodying a plurality of superposed tubular sections open at the side and each provided with the panel hinged at the edge of the opening and a plurality of locking devices for the free edge of the panel connected for simultaneous operation.
19. A mail-chute embodying a channel or body portion open at one side and having the inwardly-extending flanges at the sides of said opening and the removable panel for closing said opening and a plurality of locking devices for securing it.
20. A mail-chute embodying a channel or body portion open at one side and having the

- inwardly-extending flanges at the sides of said opening in combination with a removable panel for closing the opening hinged at one side thereof, and a plurality of locking devices for the free edge of said panel.
21. A mail-chute embodying the channel or body portion open at one side, and a door or closure hinged thereto and adapted to close said opening, in combination with a locking device for the door embodying a plurality of relatively movable engaging projections arranged on the door and body portion, respectively, the movable projections being connected for simultaneous operation.
22. A mail-chute having the opening at one side and a hinged door or closure therefor, in combination with a securing device for the door embodying relatively movable engaging members, means for retaining one of the members out of engaging position when the door is open and causing the automatic engagement of the parts when the door is closed.
23. A mail-chute having the opening at one side and a hinged door or closure therefor, in combination with a securing device for the door embodying a plurality of movable parts for securing the free edge of the door connected for simultaneous operation, means for retaining said parts out of engaging position and means, operating when the door is closed, to release said retaining device.
24. A mail-chute having the opening at one side, and a hinged door or closure therefor, in combination with a securing device for the door embodying a plurality of hook members connected for simultaneous operation, means for preventing the movement of said members to locked position and means for releasing said preventing means when the door is closed.
25. A mail-chute having the opening at one side and a hinged door or closure therefor, in combination with a securing device for the door embodying a plurality of projections, and a plurality of cooperating relatively movable plates having portions inclined relatively to the plane of movement of the projections and means for retaining the projections and plates out of locking position and means for restoring the parts to locking position when the door is closed.
26. A mail-chute having the opening at one side and a hinged door or closure therefor, in combination with a securing device for the door embodying a projection and a relatively movable locking member automatically movable to locking position and an automatic retaining device for holding the locking member out of engagement, with which the door operates when closed to release said member.
27. A mail-chute having an opening at one side and a hinged door or closure therefor, in combination with a door-securing device embodying a plurality of relatively movable engaging portions, connections between the

movable portions for causing their simultaneous operation, and a key-lock for controlling the movement of the engaging portions.

28. A mail-chute having an opening at one side and a hinged door or closure therefor, in combination with a securing device for the door embodying the relatively movable coöperating portions on the door and chute, the bar connecting the movable parts, the pivoted disk connected therewith having the cut-away portion, the pivoted locking-disk having the cut-away portion and a removable key for operating the latter.

29. A mail-chute having an opening at one side and a hinged door or closure therefor, in combination with securing devices for the door embodying coöperating projections and a pivoted disk having a cut-away portion, a lock embodying a pivoted disk having cut-away portions coöperating with the former, and controlling its movement and a removable key for operating the last-mentioned disk.

30. A mail-chute having an opening at one side to permit access to the interior and a door or closure therefor, in combination with a securing device for the door embodying a movable member, a locking device therefor and a key for the locking device and detachable therefrom only when the locking device is in position to hold the movable member of the securing device in engaging position.

31. A mail-chute having an opening at one side to permit access to the interior and a door or closure therefor, in combination with a securing device for the door embodying an automatically-movable member, a catch for holding it out of engaging position adapted to be released by the door, a locking device for the member and a key for the locking device and detachable therefrom only when the locking device is in position to hold the movable member in engaging position.

32. A mail-chute having an opening at one side to permit access to the interior and a door or closure therefor, in combination with a securing device for the door embodying the movable member, securing devices for the movable member embodying relatively movable plates having the coöperating surfaces to permit their successive operation and a key for operating one of said plates and stops coöperating therewith to prevent the removal of the key when the movable member is in unlocked position.

33. A mail-chute having an opening to permit access to the interior thereof, and a door or closure therefor, in combination with securing devices for the door embodying a movable member, securing devices for the movable member consisting of two pivoted disks each having concentric and cut-away portions, a removable key for actuating one of said members and guards with which said key coöperates to prevent its removal excepting in one position.

34. A mail-chute having an opening to permit access to the interior thereof and a door or closure therefor, in combination with the locking-bar adapted to engage the door, the pivoted disk connected thereto having the cut-away portion, the locking-disk having the cut-away portion and adapted to coöperate with the first-mentioned one, the removable key for actuating the locking-disk and the guards for preventing the removal of the key save in one position.

35. A mail-chute embodying the channel or body portion having the headed projections thereon and the supporting-brackets having the undercut recesses with which said projections are adapted to engage.

36. A mail-chute embodying two superposed sections each having at their proximate ends laterally-extending headed projections in combination with a support provided with undercut recesses, into which the projections on the sections extend.

37. In a mail-chute, the combination with a lower chute-section and an upper chute-section resting thereon each having headed projections located near their proximate ends, of a support for the sections having the undercut recesses therein into which said projections extend to secure the chute-sections in position.

38. In a mail-chute, the combination with a lower chute-section and an upper chute-section resting thereon each having the headed projections located near their proximate ends, of a holding-bracket provided with undercut recesses in which the projections extend to secure the chute-sections in position.

39. In a mail-chute, the combination with the superposed chute-sections, of a holding-bracket and coöperating headed projections and undercut recesses between the adjacent ends of the chute-sections and the bracket.

40. In a mail-chute, the combination of a lower chute-section and an upper chute-section resting upon the latter, and guides arranged between the two sections for securing their alignment and permitting the removal of the upper section.

41. In a mail-chute, the combination of a support, a lower chute-section, an upper chute-section resting upon the latter and detachable guiding connections between the sections and the support permitting vertical movement of the sections independent of the support.

42. In a mail-chute, the combination with two sheet-metal chute-sections each having the reinforcing-strips at their proximate ends provided with the headed projections, of the stationary bracket having undercut grooves for receiving the projections on the strips and holding the sections in position.

43. In a mail-chute, the combination with a plurality of separable superposed tubular sections, of stationary brackets located at the adjacent ends of the sections and separable connections between the sections and brackets

embodying headed projections and undercut recesses permitting the movement of the sections relative to the brackets in a vertical direction only.

with, of a molding-section extending over the floor-section and having flanges engaging the bracket and vertically adjustable relatively thereto.

45

50. In a mail-chute, the combination with a floor-section, and a bracket with which it engages having the projections, of the vertically-adjustable molding-section having flanges engaging the projections on the bracket.

50

51. In a mail-chute, the combination with the chute-section, a floor-section, a bracket with which both sections engage and having lateral extensions, of a molding-section having extensions engaging the bracket and vertically adjustable thereon and over the floor-section.

55

52. In a mail-chute, the combination with the bracket having the recesses and the extensions thereon, of a floor-section having projections engaging the bracket and the apron, the molding-section engaging the apron and projections engaging the bracket and a base-section with which the lower end of the molding engages.

60

53. In a mail-chute, the combination with a tubular chute-section, a bracket with which its end engages and a section embodying a vertically-extending flange engaged with said bracket and larger than the chute proper and a molding-section vertically adjustable upon said flange to finish the upper and lower ends of the chute between floors.

70

54. A mail-chute embodying a tubular conduit having mail-receiving apertures at different levels and a mail-receptacle at the lower end and a removable panel for permitting access to the interior of the chute.

75

JOSEPH WARREN CUTLER.
